DESIGN FOR A PHOTOGRAPHIC EASEL ALBUM OR SIMILAR ARTICLE

Alfred Tepel, New York, N. Y.

Application October 7, 1941, Serial No. 103,669

Term of patent 3½ years

To all whom it may concern:

Be it known that I, Alfred Tepel, a citizen of Germany, residing in the United States, in the city, county, and State of New York, have invented a new, original, and ornamental Design for a Photographic Easel Album or Similar Article, of which the following is a specification, reference being had to the accompanying drawing, forming part thereof.

Figure 1 is a perspective view of a photographic easel album showing my new design, the back of the same being plain;

I claim:

The ornamental design for a photographic easel album or similar article, as shown and described.

ALFRED TEPEL.
